William E. Badger
J. Curtis, Atty.

UNITED STATES PATENT OFFICE.

WILLIAM EZRA BADGER, OF QUINCY, MASSACHUSETTS.

GOVERNOR-VALVE.

SPECIFICATION forming part of Letters Patent No. 289,954, dated December 11, 1883.

Application filed August 24, 1883. (No model.)

To all whom it may concern:

Be it known that I, WILLIAM E. BADGER, a citizen of the United States, residing at Quincy, in the county of Norfolk and State of Massachusetts, have invented certain new and useful Improvements in Governor-Valves for Steam-Engines or other Fluid-Supplies; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to governor-valves for steam-engines and other fluid-supplies; and it consists in certain details of mechanical construction, as hereinafter explained, the object 20 of my invention being to render the governor very sensitive and quick in its operation by equilibrating the valve to the pressure of fluid.

The drawings accompanying this specification represent in Figure 1 a sectional elevation, and in Fig. 2 a longitudinal section, of a valve containing my improvement. Fig. 3 is an elevation of the valve.

In said drawings, A represents my valve, to the upper end of which is secured the lower 30 end of the stem B, which connects the valve with the governor, the valve A being contained within a case, C, through the upper head or cap of which the stem B passes, while the lower end of such case, by an opening, D, communicates with the steam-chest of a steam-engine or other object, the fluid-supply of which is to be regulated by the valve. The case C is formed with an inlet-port, E, at its upper part for admission of steam to its interior. 35 The valve is a straight tube, having upon each end an annular rib, the upper rib being shown at a and the lower at b, and these two ribs operate with a tubular cylinder or cup, F, secured to or formed upon the inside lower part 40 of the case C, the upper and lower ends, a' b', of this cylinder constituting valve-seats, to operate with the ribs a b of the valve. The up-

per end of the cup F is open, while its lower end is covered with a bottom, c, and its sides contain ports d d, &c., for escape of steam. 50 Steam entering at E flows around and through the valve and escapes at D in greater or less quantities, according to extent to which the valve is opened or closed. It will be seen that as the valve is a straight cylinder open at both ends and with each end of uniform diameter, and operating each with a valve-seat, a or b, the pressure of fluid is uniformly distributed upon all parts of the valve, and the latter thereby becomes perfectly balanced or equilibrated 60 to such pressure; hence very little power is required at the hands of the governor to move the valve, and the two are rendered very sensitive in their operation.

In order that the fluid may be admitted to 65 the case C in a smooth and easy flow, and thereby prevent any tendency to hammering movement of the valve, I form the lower part of each port d of the cup F pyramidal in shape, as shown in Fig. 1 of the drawings, the fluid 70 by this means being let on or shut off gradually. To enhance this effect, I form the upper flange, a, of the valve deeper than the lower one, and I form in such flange pyramidal recesses e e, &c., through which fluid flows into 75 the cup F.

I claim—

The case C, having an inlet, E, whereby steam enters above the valve, and an outlet, D, below the valve, in combination with hollow valve 80 A, which is open at the bottom and has openings in its top, and cup F, provided with openings d in its side and valve-seats a' and b', the said hollow valve being provided with external flanges, a and b, of approximately equal 85 diameter, corresponding to said valve-seats, the whole constituting a balanced valve, substantially as set forth.

In testimony whereof I affix my signature in presence of two witnesses.

WILLIAM EZRA BADGER.
